DESIGN FOR AN IRONING MACHINE

Fred A. Conterman, Jamestown, N. Y., assignor to Blackstone Manufacturing Company, Inc.,
Jamestown, N. Y., a corporation of New York

Application May 28, 1938, Serial No. 77,459

Term of patent 7 years

To all whom it may concern:

Be it known that I, Fred A. Conterman, a citizen of the United States, residing at Jamestown, in the county of Chautauqua and State of New York, have invented a new, original, and ornamental Design for an Ironing Machine, of which the following is a specification, reference being had to the accompanying drawing, forming part thereof; and in which

The other side of the ironer shoe and gear casing is substantially plain.

The design is characterized by an ironing machine of the specific contour shown, the end supports and cover thereof having horizontal ribs of the form shown disposed thereon in the specific relation illustrated.

I claim:

The ornamental design for an ironing machine, substantially as shown and described.

FRED A. CONTERMAN.
